UNITED STATES PATENT OFFICE.

AARON BERKOWITZ, OF NEW YORK, N. Y.

HAND-OPERATED GUMMED-BINDING SEALER.

1,307,891.

Specification of Letters Patent. Patented June 24, 1919.

Application filed August 30, 1918. Serial No. 252,112.

To all whom it may concern:

Be it known that I, AARON BERKOWITZ, a citizen of the United States, and a resident of the city of New York, borough of the Bronx, in the county of Bronx and State of New York, have invented a new and Improved Hand-Operated Gummed-Binding Sealer, of which the following is a full, clear, and exact description.

10 This invention relates to devices for applying a gummed sealing label or strip to boxes, cartons, or other packages, and has particular reference to means for applying such labels or strips practically automatically.

15 Among the more particular objects of the invention is to provide a hand operated device carrying a roll of gummed binding and means for moistening the strip of binding as it is unrolled from the roll and applied to the box or package, the unrolling, moistening and pasting of the binding being accomplished by the simple movement of the device along the box or package.

20 25 Another object of the invention is to provide a hand operated device for applying a strip of gummed binding, the same being provided with means to automatically sever the applied portion of the strip from the roll when the end of the box or package is reached, or elsewhere.

30 35 A still further object is to provide a device for applying a strip of gummed binding, and at the same time print upon the face thereof a legend pertinent to the shipper of the package.

40 45 Again, an object is to provide in a hand operated gummed binding sealer special guiding means whereby the binding may be applied either along the corner of a box or along a joint intermediate of the edges of one side as well as upon any smooth surface.

50 55 With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had

to the accompanying drawings, in which like reference characters designate the same parts in the several views, and in which—

Figure 1 is a perspective view showing the device in operative position.

Fig. 2 is a vertical longitudinal sectional view.

Figs. 3 and 4 are detail elevations of the front end of the device showing two different positions of the guiding means.

Fig. 5 is a detail view of the rear portion indicating the action of the automatic means to sever the pasted portion of the strip from the roll at the end of the box or package.

Fig. 6 is a horizontal sectional detail on the line 6—6 of Fig. 4.

Fig. 7 is a perspective view of the moistening roll; and

Fig. 8 is a detail plan view indicating the manner of marking the pasted strip.

Referring now more specifically to the drawings, I show a device of the character indicated comprising a rigid frame having a skeletonized front portion 10, and a rear portion 11. The frame comprises essentially right and left side portions lying in parallel vertical planes, and between which there are crossbars 12, 13, 14, and 15. A handle 16 is rigidly connected to the bars 12 and 13 in position for convenient control or operation of the device. In addition to the crossbars there is provided at 17 a shoe shown as of hollow or semi-tubular construction, the lower portion of which constitutes a squeegee or pressing member for the strip of binding *b* as it is being applied to the package or box. The shoe is provided just ahead of the bearing portion with a transverse slot 17'. This shoe 17 is fixed between the side plates of the main frame and is immovable with respect thereto.

The main roll *B* of the binding with dry gum applied thereto on its under or inner face is mounted upon a bar 18 supported at the upper front portion of the frame. Said bar 18 is adjustable up and down along slots 19 formed in the diagonal bars 20 of the sides of the frame so as to bring the roll at the most convenient position for the operator.

Below and at the rear of the roll *B* is a

moistener roll comprising a chamber 21 for water and having perforations 21' through which the water may ooze in small quantities into and through a fabric pad 22 of any suitable nature for the application of the moisture to the gummed surface of the strip which is guided thereover and held in moderate contact therewith by means of a guide roller 23. From the rear portion of the moistener roll the end of the binding strip is guided down beneath the forward portion of the shoe 17 and is always in convenient reach for initiating the application thereof to a box or package in properly moistened condition. When the end of the strip is thus secured the movement of the device forward will automatically apply the gummed strip to the box or package, or as much of the strip as desired.

20 Journaled in the lower rear portion of the frame on a transverse axis 24 parallel to the axes of the tank 21 and roll B is a printing roll 25 carrying on its surface one or more rubber stamps 26, or their equivalent, 25 adapted to coöperate with an inking roll 27 journaled on the main frame just above the printing roll, and from which ink is delivered to the rubber stamps automatically with the rotation of the roll 25, whereby I 30 am able to imprint any suitable sign, mark, or legend upon the face of the strip b simultaneously with the applying of said strip to the box or package, as for example as plainly indicated in Fig. 8. As shown the 35 marks or legends 26' are arranged along the edges of the strip and so that one series may be read in one direction and another series in an opposite direction. This feature is especially useful when applying the 40 binding strip along the edge or corner of a box or package.

At the front lower portion of the main frame and held between the crossbars 14 and 15 is a peculiar form of guiding device 28 45 of angular formation in cross section and comprising a wide blade 28^a and a narrow blade 28^b and adapted to be rotated or adjusted around a longitudinal axis determined by the pivots 29. For the application 50 of the gummed strip to any ordinary smooth surface, the guiding device 28 is adjusted as shown in Figs. 1 and 2 with the blade 28^a horizontal and the blade 28^b upright. When, however, the strip is to be applied to 55 the corner of the box or package as indicated in Fig. 3, the guide 28 is adjusted so as to bring the blade 28^a at one side of the corner while the frame as a whole operates along the other side of the corner. This 60 guide, therefore, constitutes a means to insure that the longitudinal center of the strip will be applied directly over the corner of the box. In this position of the strip the two series of legends 26' will be visible on

the two right angularly disposed surfaces of 65 the sealed package. The means for adjusting and holding the guide in adjusted position comprises a lever 30 consisting essentially of a leaf spring fixed at the front pivot 29 and having a stud 31 adapted to snap 70 into any one of a series of holes 32, 33, or 34 formed in an arc shaped vertical plate 35 fixed to the front crossbar 14. This lever is provided with a finger piece 36 for the convenient manipulation thereof. In the sealing of cartons such as are commonly used nowadays for the shipment of merchandise the sealing strip is applied over the longitudinal center of the carton where the two outermost top flaps meet. The blade 28^b 80 of the guide 28 consequently serves to hold the apparatus in its movement along the center of the carton, the blade projecting into the slot or crack between the two outermost flaps, or the meeting line of the two 85 adjacent free edges of said flaps. This blade, however, is made narrower than the other so as not to interfere with the inner portions of the carton.

The means indicated for severing the 90 pasted portion of the strip from the unpasted portion includes a knife blade 37, fixed to and carried by a yoke 38 pivoted at 39 upon a pair of upward extensions 40 of the main frame, the axis of the pivot shown 95 as just above the moistening roll 21. The rear portion of the yoke is carried at the rear of the main frame and just above the bottom surface thereof. The knife blade 37 is carried normally within an upward depression 100 10^a of the frame and abutting against a pair of shoulders 41 just back of the crossbar 15. This position of the yoke and blade is determined by the action of a spring 42 of any suitable construction acting between the 105 fixed frame and the movable yoke. The blade 37 is so designed as to swing rearward in an arc of a circle whose center is the pivot 39 and into slot 17' of the shoe 17 as indicated in Fig. 5, the blade having a central 110 point to facilitate this movement into the shoe and through the binding strip. This actuation of the blade for the purpose of cutting off the strip may be effected at any time by the swinging of the yoke around its 115 pivot 39. Usually the strip is to be cut off just over the end of the box or package so that the machine may be operated by hand directly over the end of the box as shown in Fig. 5, the main frame dropping over the 120 end while the yoke resting upon the end portion of the box causes the swinging of the knife as indicated. This leaves a short piece of the strip to be sealed over the end of the box. If, however, the strip is to be severed 125 at a point prior to the reaching of the end of the box it may be effected by simply tilting the device upward around the rear por-

tion of the frame as an axis, thus causing the rear end of the yoke to be swung upward relatively.

A machine or device made in accordance with this invention is relatively simple and cheap in construction, easy to operate, and in the practice of the same in the sealing of boxes or packages the binding strips are applied uniformly and neatly with the least expenditure of time or waste of material.

I claim:

1. The combination with a main frame adapted to carry a supply of binding gummed on one surface, and means to moisten the binding as it is drawn through the frame, of a guiding member carried by the main frame serving to guide the frame along the edge of the box or package to insure the application of the binding with its longitudinal center along the edge of said corner, and means to automatically apply a printed legend along one edge of the binding strip simultaneously with the application thereof along the corner of the box or package.
2. In a device of the character set forth, the combination with a main frame, means to manipulate it along a box or package, and means carried by the frame to apply a gummed binding while in motion, of a longitudinal guiding member L-shaped in cross section thus having two blades, one narrower than the other, and means to hold the guiding device with either of said blades projecting downward.
3. The combination with a main frame, means to manipulate it along a box or package to be sealed, and means to apply a strip of binding to said box or package, of a longitudinal guiding member L-shaped in cross section pivotally supported in the

lower portion of the frame with its axis longitudinal of the direction of movement of the device, a finger piece connected to the guide, and an arc shaped holder for the finger piece serving to lock the guiding member in any selected one of a number of different positions, substantially as set forth.

4. In a gummed binding sealer for sealing boxes or packages, the combination with a main frame and means to deliver moistened binding therefrom to a box or package, of means to automatically sever the applied portion of the binding from the unapplied portion when the end of the box or package is reached, said severing means including a cutter and a support for the cutter movable relatively to the frame and caused to be moved by contact with said end of the box or package.

5. In a gummed binding sealer, the combination with a main frame, means to manipulate the frame, and means to deliver a moistened gummed strip therefrom to a box or package, of a cutter serving to sever the applied portion of the binding, and a carrier for the cutter operative to actuate the cutter automatically when the main frame is operated over the end of the box or package.

6. In a gummed sealing binder, the combination with a main frame, means to manipulate the frame, and means to deliver a moistened gummed strip therefrom to a box or package, of a yoke pivoted to the frame, and a cutter carried by the yoke and serving to automatically sever the applied portion of the binding from the unapplied portion when the yoke is brought into bearing contact with a relatively fixed object.

AARON BERKOWITZ.
